UNITED STATES PATENT OFFICE.

JOHN C. HARDENBERGH, OF CLEVELAND, OHIO.

DOOR-LOCK.

No. 804,399.

Specification of Letters Patent.

Patented Nov. 14, 1905.

Application filed March 30, 1905. Serial No. 252,832.

To all whom it may concern:

Be it known that I, JOHN C. HARDENBERGH, a citizen of the United States, residing at Cleveland, in the county of Cuyahoga and 5 State of Ohio, have invented new and useful Improvements in Door-Locks, of which the following is a specification.

This invention is a combined door lock and latch having key mechanism in one of the 10 knobs.

It is characterized particularly by a clutch, one member of which operates the latch-bolt and the other member of which is carried by the outside knob, and the knob-spindle may 15 be moved lengthwise to engage or disengage the clutch. Key-operated means are provided to turn the spindle from the outside when the clutch is disengaged. On the inside means are provided to lock the clutch at disengagement.

The invention is illustrated in the accompanying drawings.

Figure 1 is an edge view of a door with the lock in elevation. Fig. 2 is a vertical section with the clutch engaged. Fig. 3 is a vertical section with the clutch disengaged. Fig. 4 is a section on the line 4 4 of Figs. 2 and 3. Fig. 5 is a section on the line 5 5 of Figs. 2 and 3. Figs. 6 and 7 are details in elevation 30 showing the latch on the inside of the door which holds the clutch in or out of engagement. Fig. 8 is a horizontal section through the edge of the door, showing the latch in plan. Fig. 9 is a plan of the key.

Referring specifically to the drawings, 35 6 indicates the inside knob and 7 the outside knob. The former is fixed to the knob-spindle 8. The latter is fixed to a clutch member or sleeve 9, which is rotatable on a round portion 10 of the knob-spindle. This clutch member has teeth which engage with a corresponding clutch member 11, which is located on the squared portion of the knob-spindle and turns therewith. The member 11 carries the lugs 40 45 12, which operate the latch-bolt 13.

14 indicates a circumferential rib on the spindle between the squared portion 8 and the round portion 10, and the sleeve 9 abuts against this shoulder, so that it may be moved 50 lengthwise with the knob-spindle to engage or disengage the clutch members.

At the outer end beyond the round portion 10 the knob-spindle has a reduced squared portion 15, over which is sleeved a nipple 16 of a circular lock-casing 17. The nipple is fast on the 55 squared portion 15. This casing is rotatable

in the knob, or, rather, the knob is rotatable upon the casing; but when the casing is turned it also turns the knob-spindle by means of the squared connection between 15 and 16. 60 The knob and casing have a keyhole 18 to receive the key 19, which has a bit 20, adapted to project through a notch at 21 in the inner wall of the casing and into a notch at 22 in the outer end of the clutch member 9, thereby 65 locking the knob and casing together, so that when the knob is turned the casing and spindle will also be turned. The keyhole 18 is staggered with respect to the notch 21, so that when the key is inserted it must first be 70 turned in the casing before its bit can enter the notch.

The face-plates upon the inside and outside of the door are indicated, respectively, at 23 and 24, and the latter has a tubular portion 75 25, in which the outer clutch member 9 turns. The shank 26 of the inside knob has therein a groove 27 to receive the forked end of a sliding latch 28, normally pressed down by a spring 29. This latch-piece slides in guides 80 in the face-plate 23 and acts to hold the clutch members 9 and 11 in or out of engagement.

When used as an ordinary latch, the inside knob is pulled out, as shown in Fig. 2, with the latch 28 engaging behind the rib 30 on the 85 shank of the inside knob. This draws the member 9 inwardly and holds the clutch members together, so that when either knob is turned the latch will be operated. When used as a lock, the latch 28 is lifted and the 90 inside knob is pushed in a sufficient distance to disengage the clutch member 9 from the member 11. If then the outside knob be turned, it will simply rotate the clutch member 9 upon the round portion 10 of the spindle 95 without operating the door-latch; but if the key 19 be inserted as described the casing 17 and knob will be locked together and the casing will turn with the knob, which motion, by means of the squared portion at 15, will 100 be communicated to the knob-spindle, and thus to the door-latch.

What I claim as new, and desire to secure by Letters Patent, is—

1. In a combined latch and lock, the combination of a bolt-actuating spindle having one knob fast and another rotatable thereon, the spindle having thereon one clutch member and the loose knob having another clutch member also rotatable on the spindle, the 105 spindle and knobs being slid able lengthwise to engage or disengage said clutch members,

and key-operated means to lock the loose knob and the spindle together when the clutch is disengaged.

2. In a combined door lock and latch, in combination, a bolt-actuating spindle having an inside knob fast thereon and an outside knob rotatable thereon, clutch members carried by the spindle and loose knob respectively, the spindle being slidale lengthwise to engage or disengage the clutch, a latch on the inside of the door engageable with the

spindle to hold the clutch as set, a casing fixed to the spindle within the loose knob and on which said knob is rotatable, and means to lock the knob and casing together.

In testimony whereof I have signed my name to this specification in the presence of two subscribing witnesses.

JOHN C. HARDENBERGH.
